ATTORNEY.

UNITED STATES PATENT OFFICE.

CHRISTIAN F. BACHLER, OF PHILADELPHIA, PENNSYLVANIA.

ATOMIZER.

SPECIFICATION forming part of Letters Patent No. 447,599, dated March 3, 1891.

Application filed November 17, 1890. Serial No. 371,696. (No model.)

To all whom it may concern:

Be it known that I, CHRISTIAN F. BACHLER, of Philadelphia, in the county of Philadelphia and State of Pennsylvania, have invented certain new and useful Improvements in Atomizers; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to certain improvements in atomizers. The devices of this class ordinarily employed become loose and allow vent at the cork or stopper, hence allowing the pressure in the bottle to reduce, and, further, they become clogged and can only be used in certain bottles.

The object of this invention is to provide an improved atomizer exceedingly simple, cheap, and durable in construction, and extremely effective and sure in operation, and which will overcome all disadvantages of the present devices of this character, will prevent all leakage at the stopper, can fit almost any-sized bottle, and can be taken apart for cleansing or repairing. These objects are accomplished by, and this invention consists in, certain novel features of construction and in combinations of parts more fully described hereinafter, and particularly pointed out in the claims.

Referring to the accompanying drawings, Figure 1 is a sectional elevation of a bottle, showing the atomizer therein in elevation. Fig. 2 is a longitudinal section of the atomizer, the liquid-discharge tube being shown in elevation. Fig. 3 shows the various parts of the atomizer separated and in elevation. Fig. 4 is an elevation of the discharge end of the preferred form of liquid-tube, and Fig. 5 is a section showing the preferred form of liquid-tube in the discharge end of the air-chamber.

In the drawings, the reference-letter *a* indicates any suitable bottle. *b* is the liquid-discharge tube of the atomizer of a length to extend down into and almost to the bottom of the bottle and project above the same,

with the upper end bent at or substantially at right angles and having its discharge end slitted back, substantially as shown at *c*. An air-inlet tube *d* surrounds the upper portion 55 of the liquid-discharge tube and extends into the bottle. This air-tube is larger in diameter than the liquid-tube, forming an annular air-passage around the same, open at the top to the outer atmosphere and at its inner end 60 into the interior of the bottle. The inner end of the large air-tube is slotted or slotted longitudinally, forming spring-fingers *e*, which bear against the discharge-tube, while the slits form openings from said annular air-passage 65 into the bottle. This air-tube also forms the stem or spindle of an expandible bottle-stopper, and is exteriorly screw-threaded the upper portion of its length. Near its lower end this tube has an exterior annular collar *f* 70 rigid thereon, (preferably integral therewith,) against which the lower end of the expandible rubber tube *g*, slipped onto the tube, fits. *h* is the upper movable member of the stopper slipped onto said tube and bearing down on 75 said elastic ring, tube, or member and having the upper exterior annular flange *i* to rest on the upper edge of the bottle-neck. *j* is a washer, and *k* is the winged nut adjustable on the threaded portion of said air-tube to 80 operate the stopper. An air bulb or chamber *l* is located on the upper end of said air-tube surrounding said bent end of the discharge-tube. Said chamber is preferably formed integral of metal with a screw-threaded opening *m* in its bottom opening into the large portion of the chamber and screwed onto the upper end of the air-tube, so that the air can pass from said chamber into the air-tube. At one end said chamber has the elongated discharge-mouth *n*, beveled outwardly at its outer end, and at its opposite end a screw-threaded opening *o*, into which the perforated piece *p* screws. The discharge-tube extends up through the air-pipe into said chamber 85 with its bent end extending into said contracted discharge, but not completely through the same, and so as to leave a narrow air-passage around said slitted end of the discharge-tube. The central portion of said bulb preferably bulges out to form an enlarged air-chamber which serves as a reservoir, causing 90 95 100

some of the air to flow into the air-tube and the remainder to pass through the contracted discharge-opening, thereby creating sufficient pressure to force the liquid in the bottle out

5 through the discharge-tube, while the air passing out around the slotted discharge end of said tube atomizes the liquid and carries it out with great force in fine spray, the spray being ejected in a large volume and to a considerable distance.

In order to render the device capable of use in bottles of various depths, the liquid-discharge tube below the air-inlet tube may be made telescopic, as shown. The lower 15 sliding section *q* may be closed at the lower end and provided with side apertures *r*, so that it can rest on the bottom of the bottle, and hence take up all of the liquid in the bottle.

20 The prongs or fingers *s*, formed by the slits at the end of the liquid-discharge pipe, are preferably flared out, (see Figs. 4 and 5,) hence holding the tube in the center of discharge *n* and against movement in the bulb; also causing the liquid to be thoroughly atomized.

The atomizer can be applied to almost any bottle. The stopper forms an air-tight joint within the neck of the bottle, which cannot wear loose and allow vent of air, and holds 30 the parts rigid and the liquid-tube against swinging in the bottle.

All parts of the article are made separate and are removable and interchangeable, and the article can be taken completely apart to 35 clean, replace, or repair the various parts, and all interior portions are accessible, so that they can be cleaned and prevented from clogging.

The many advantages and great utility of 40 the article are obvious.

This article is adapted for various uses, such as spraying tobacco, clothes, extracts, or any liquid.

What I claim is—

1. In combination, the liquid-discharge tube 45 having the upper discharge end, the air-inlet tube surrounding said discharge-tube, the air-chamber carried by the air-tube and surrounding the discharge end of said liquid-tube, and an expansible bottle-stopper to support said 50 atomizer, consisting of an expansible section and rigid sections on and surrounding said air-tube.

2. In an atomizer, the combination of the liquid-tube, the air-inlet tube exteriorly 55 threaded having the rigid exterior collar, the elastic and sliding members of an expansible stopper on said air-tube, and the expanding nut of the stopper on said tube.

3. The atomizer having the lower portion 60 of its liquid-discharge tube telescopic, substantially as described.

4. In an atomizer, the combination of the inner liquid-tube, the air-tube removably on the same and having the threaded upper end 65 and a stopper, the air-chamber having the elongated contracted discharge and the small threaded opening opposite said discharge, and the threaded bottom opening screwed onto the upper end of said air-tube, and the 70 contracted mouth-piece having the small threaded end screwed into said opening opposite the discharge, as set forth.

In testimony that I claim the foregoing as my own I affix my signature in presence of 75 two witnesses.

CHRISTIAN F. BACHLER.
